UNITED STATES PATENT OFFICE.

FRANK L. LATHROP, OF WALLINGFORD, CONNECTICUT, ASSIGNOR TO THE
H. L. JUDD & COMPANY, OF NEW YORK.

DESIGN FOR A CURTAIN-RING.

SPECIFICATION forming part of Design No. 29,574, dated November 1, 1898.

Application filed October 4, 1898. Serial No. 692,645. Term of patent 14 years.

To all whom it may concern:

Be it known that I, FRANK L. LATHROP, a citizen of the United States, residing at Wallingford, New Haven county, Connecticut, 5 have invented a certain new and original Design for Curtain-Rings, of which the following is a full, clear, and exact description.

My invention relates to a new and original design for curtain-rings.

10 In the accompanying drawings, Figure 1 is a perspective view of an embodiment of my new and original design. Fig. 2 is a front elevation of the design perspectively shown in Fig. 1.

15 To the eye the curtain-ring appears substantially as follows: A is a round portion bent so as to form a curve approximating a circle, but without the ends thereof being joined so as to form a complete circle. In

the interrupted portion of the circle—that is, 20 between the ends of the part A—are thin objects B B, of circular form. Upon the flat faces of the objects B B are lateral projections C C, also circular in outline, but of considerable less diameter than the diameter of 25 the objects B B. The projections C C appear to be in substantially the central portion of the objects B B.

What I claim is—

The design for a curtain-ring substantially 30 as herein shown and described.

Signed at Wallingford this 1st day of October, 1898.

FRANK L. LATHROP.
